UNITED STATES PATENT OFFICE.

ERNEST OLDENBUSCH, OF HOBOKEN, NEW JERSEY.

DESIGN FOR A FRAME FOR PICTURES OR SIMILAR ARTICLES.

SPECIFICATION forming part of Design No. 34,260, dated March 26, 1901.

Application filed February 7, 1901. Serial No. 46,452. Term of patent 31 years.

To all whom it may concern:

Be it known that I, ERNEST OLDENBUSCH, a citizen of the United States, residing at Hoboken, in the county of Hudson and State of New Jersey, have invented and produced a new and original Design for Frames for Pictures or Similar Articles, of which the following is a specification, reference being had to the accompanying drawings, forming part thereof.

Figure 1 is a plan view of a frame for pictures or similar articles, showing my new design. Fig. 2 is a sectional view taken on the line 2 2 of Fig. 1. Fig. 3 is a sectional view taken on the line 3 3 of Fig. 1.

As shown in the drawings, the leading or material feature of my design consists of a plain concave elliptical rim A, to the outer edge of which are attached the ornamental scrolls D, forming a border, and the whole

being surmounted by the ornamental piece c, having a plain center d and floral ornamentation e.

It is apparent that this design is also applicable to frames for mirrors and similar articles. 25

Having described my invention, what I claim as new, and desire to secure by Letters Patent, is—

The design for a frame for pictures or similar articles, substantially as herein shown and described. 30

In testimony whereof I have signed my name to this specification in the presence of two subscribing witnesses.

ERNEST OLDENBUSCH.

Witnesses:

NELSON H. STEWART,
MARTHA W. JONGHMANS.
